APPARATUS FOR AND METHOD OF QUENCHING

Howard E. Somes, Detroit, Mich., assignor to Bur. Induction Heating, Inc., Philadelphia, Pa., a corporation of Michigan

Application November 21, 1941, Serial No. 419,828

11 Claims. (Cl. 148—21.55)

This application is a continuation in part of my copending application Serial No. 336,129, filed May 20, 1940, for heat treating apparatus which has matured into Patent 2,358,834.

This invention relates to a method of quenching articles during a heat treating process with respect to which it is desired to improve the physical characteristics thereof by zone hardening, and to the apparatus for carrying out the quenching operation. Although the present invention is applicable to the heat treatment of the external surfaces of cylindrical members, it is particularly directed to the progressive heat treatment by electro-magnetic induction of the inner surfaces of hollow articles, such as, for example, engine and pump cylinders, tubular pipe for oil well casings and drill rods or for structural purposes, gun barrels and other tubular members.

In the magnetic induction heating of cylindrical members, differential heating is accomplished through the concentration of high power, high frequency heating currents in an annular surface zone to be hardened. These heating currents are caused to uniformly flow almost entirely in the annular zone being heated and are so concentrated that the temperature of the zone affected is raised to hardening temperature before any substantial amount of heat can drift to the core or the back metal of the piece immediately adjacent such zone. The required heat is almost instantaneously generated in this zone to a uniform radial depth throughout the same.

It is the primary object of the present invention to so quench the heated zone that the thermal energy is removed not only at substantially the same rate as that at which it was generated but also uniformly throughout the annular extent thereof, and with a minimum of elapsed time between the termination of the heating operation and the application of the quenching medium.

Another object is to bring the foregoing about as will hereinafter appear through the accurate control of such features entering into the quenching operation as the character of flow and distribution of the quenching medium, the relation of the time and rate of quenching medium application with respect to the heat operation and the proximity of the quenching apparatus to the surface of the zone being heat treated.

A further object is to provide new and improved quenching apparatus of simple and economical yet, extremely efficient construction capable of discharging a solid annular wall of quenching medium at desired velocity and volume into uni-

form contact with a heated cylindrical surface with a minimum of turbulence.

With the above and other objects in view, which, from the following detailed description, will be apparent to those skilled in the art to which the invention appertains, the present invention consists in certain steps in the new and improved method and in certain features of construction and combinations of parts to be hereinafter described with reference to the accompanying drawings and then claimed.

In the drawings in which one suitable embodiment of the quenching apparatus has been selected for the purpose of illustration of the present invention,

Figure 1 is a vertical section of the quenching head in cooperative association with an induction heating head;

Figure 2 is a transverse section taken approximately on the line 2—2 of Figure 1 showing certain of the axial passages for the flow of quenching medium;

Figure 3 is a transverse section taken approximately on the line 3—3 of Figure 1; and

Figure 4 is a greatly enlarged fragmentary section taken through the two annular members to more clearly show the conical passageway defined by these two members, the support for the inner member being indicated in broken outline.

Referring to the accompanying drawings in which like numerals refer to like parts throughout the several views, there is shown in Figure 1 one suitable embodiment of a quenching head Q in operative association with an induction heating head H, the heating head H being of the general character shown in my said copending application Serial No. 336,129, suitable for heat treating the internal surface of a tubular cylinder C throughout an annular zone Z to a predetermined uniform depth.

Briefly the induction heating head H, which structurally forms no part of the present invention, comprises a tubular heating coil 6 carried by a laminated magnetic core 7 which in turn is carried by a suitable mandrel or conductor 8, one end of the coil 6 extending through the conductor 8 in communication with a ported chamber 9, a part of which is normally closed by a suitable valve such as a ball element 8a. The coil 6 is cooled by the passage of a suitable coolant therethrough which exhausts into the chamber 9. When the head H is operative to induce heating currents in the workpiece C, the ball element 8a is raised from its seat to permit the coolant to

discharge through the port of chamber 9 in a manner to be hereinafter described.

Although not shown in the drawings the heads H and Q are normally spaced apart, and after the workpiece or tube C to be heat treated is located by means of any suitable work holder (not shown) in proper position for heat treatment the induction heating head H and the quench head Q are brought into axial registration, as illustrated in Figure 1. The lower end of the tube C at this time is axially upwardly beyond the heating coil 6. The tube C is then propelled downwardly relative to the heads H and Q at a uniform rate of travel and at a predetermined time with respect to the downward travel of the tube C the coil 6 is connected with its source of high frequency energy and the head Q is connected with its source of quenching medium. During this movement in a downward direction, as viewed in Figure 1, the internal surface of the tube C is progressively heated and quenched, the tube or heads also being rotated during such movement to insure uniform application of the heating currents and the quenching medium. It is to be appreciated, of course, that the heads H and Q may be axially moved instead of the tube and, also, that the tube and heads may be disposed for relative axial movement in a horizontal direction instead of in the vertical direction, shown in Figure 1, for performance of the heat treating operation.

Before describing the method of the present invention, the quenching apparatus will first be described in detail in order that a clear understanding may be had of the same. The quenching apparatus is extremely simple in construction since it merely embodies three parts, namely, a main stem or supporting arbor 10, a first annular member 11 carried by the arbor 10 and a second annular member 12 carried by the member 11 and cooperating therewith as will soon appear to provide the passages and nozzle orifice for the quenching medium. These elements are constructed of suitable corrosion resistant material, such as, for example, stainless steel.

The arbor 10 is tubular in cross-section for a portion of the length from its lower end to provide a chamber 13 within the bore thereof to receive quenching medium, such as water under high pressure, from a support (not shown) to which it is secured by means of internal threads 14. The upper or solid end of the arbor is provided with external screw threads 15 and a circumferential chamber 16 intermediate the threads 15. This chamber receives the quenching medium from the chamber 13 through a plurality of generally axial passages 17 communicating with the chamber 13 through the bottom of the bore of the arbor 10. It is preferred that the total transverse area of passages 17 be at least about one-half the transverse area of the chamber 13 in order to provide an increase in velocity of the quenching medium flowing therethrough.

The first annular member 11 is generally tubular, it having a narrow cylindrical head 18 at its upper end, as viewed in the drawings, a cylindrical outer surface 19 of reduced diameter intermediate its ends, an externally threaded portion 20 adjacent its lower end terminating adjacent the cylindrical portion 19 in a circumferential recess 21 to provide a downwardly facing shoulder 22, and a conical surface 23 extending between the head 18 and the cylindrical surface 19. The conical surface 23 inclines in axial cross-

section upwardly and outwardly from the upper end of the cylindrical portion 19 and terminates radially inwardly of the periphery of the head 18 to form therewith a downwardly presented annular groove 24. As seen in Figure 4, the bottom wall 25 of the groove 24 is arcuate in contour, it being tangent at one side to the conical wall 23 and tangent at the other side to a downwardly and outwardly inclined conical wall 26 of appreciable length which terminates substantially at the lower peripheral edge of the head 18.

The purpose of the downwardly presenting annular groove 24 is, as will later appear, to divert a generally upward flow of the quenching medium to a general downward flow.

The cylindrical portion 19 of the member 11 is provided with upper and lower rows of radial passages 27 extending therethrough, the passages of one row being staggered with respect to the passages of the other row. The transverse sectional area of the individual passages is relatively small, there being as many as 60 such passages in such cylindrical surface having a diameter, for example, of $2\frac{1}{2}$ ", whereby such small passages will tend to minimize the turbulence of the flowing quenching medium.

The second annular member 12 is of substantially the same external diameter as the member 11 and the lower portion of its internal wall is cylindrical and threaded as indicated at 28 and being recessed to provide a radial shoulder 29 and a cylindrical surface 30 of a diameter very slightly greater than that of the cylindrical surface 19 of the member 11. The upper portion of this inner wall is of conical formation, tapering upwardly and outwardly at 31 from the cylindrical surface 30, the region at which such taper is initiated being spaced radially outwardly an appreciable distance from the cylindrical surface 30. The annular upper end of the member 12 is in the form of a convex arcuate surface 32 tangent at one end termination to the surface 31 and tangent at its other end termination to a downwardly and outwardly inclined wall 33 which extends to the outer periphery of the member 12 near the upper end thereof. As seen in the drawings, particularly Figure 4, the angle of inclination of the wall 33 is the same as that of the wall 26 of the member 11 and the angle of inclination of the wall 31 is greater than that of the wall 23 of the member 11 so that these walls converge from the cylindrical surface 19 toward each other. The arcuate walls 25 and 32 terminate at the radially inner ends of the spaced conical walls 26 and 33 which provide the orifice for the discharge of the quenching medium. It is to be noted that this orifice is continuously open circumferentially, and free from any projections which might tend to produce turbulence.

The member 12 is threadedly received on the member 11 as shown in Figure 1 and in assembled relation the shoulder 29 of the member 12 abuts the shoulder 22 of member 11 to predetermine the relative threading movement of these two members toward each other and thereby provide for a predetermined axial spacing between the bottom wall 25 of the groove 24 and the convex surface wall 32 of the member 12. It will be seen that the part of the cylindrical portion of member 11 which is disposed below the lower row of passages 27 is received within the cylindrical surface 30 in close relation therewith.

The inner surface of the inner annular member 11 is provided with a radial shoulder 35 and is internally threaded to be threadedly received

by the threads 15 of the mandrel 10 with the shoulder 35 firmly abutting a corresponding radial shoulder spaced slightly from the upper end of the mandrel 10 in an axial direction to properly axially locate the member 11 on the mandrel 10.

It is to be noted that the inner wall of member 11 is provided with a circumferential channel 36, rectangular in cross-section, intermediate the ends of the threads thereof and into which the radial passages 27 open. When the member 11 is assembled to the mandrel 10 the channel 36 is in exact registration with the channel 16 of mandrel 10 to provide an annular chamber within the members 10 and 11.

These two members, 10 and 11, provide a continuous passageway for the quenching medium from the chamber 13 of the mandrel 10 through the passages 17 into the chamber defined by the channels 16 and 36, thence through the radial passages 27 into the annular chamber 37 defined by the converging conical walls 23 and 31, and finally through the space between the parallel walls 26 and 33 in a direction away from the direction of movement of the heads "H" and "Q" as represented by the arrow 38 into angular contact with the inner surface of the tube C.

The radial passages 27 for the flow of quenching medium from the chamber provided by the channels 16 and 26 are so arranged and contoured as to insure a high velocity flow of the quenching medium with minimum turbulence. These passages are of primary importance in producing proper flow of the quenching medium. The quenching medium is introduced to the chamber 13 under high pressure which at times may be as great as, for example, 60 pounds per square inch or more and is discharged at high velocity substantially free from turbulence, the passages 17 causing a first increase in velocity. The small passages 27 being of a total area at least as great as that of the openings 17 serve, by reason of their small individual area, to straighten the quenching medium flow to an even radial flow into the chamber 37 where the velocity is this time greatly increased up to the point of entrance into the discharge orifice between the parallel walls 26 and 33. This is due to the fact that the area of this chamber uniformly decreases throughout its extent from the cylindrical wall 19 to the space between the arcuate surfaces 24 and 32. Moreover, the walls of this chamber are free from sharp turns and are extremely smooth. In order to insure smoothness of the surfaces with which the quenching medium contacts, such surfaces are hardened and surface finished, and, in fact, may be highly polished.

The area of the circumferential orifice is preferably about one-half that of the area of the openings 27 whereby to greatly increase the velocity of the quenching medium. During the passage of the quenching medium therethrough the flow is again quieted since the walls 26 and 33 are parallel and of appreciable length with the result that the quenching medium is distributed in the form of a solid conical wall substantially free from turbulence. In other words, the flow of quenching medium at each radial plane is solid, in a straight line and in a direction away from the direction of movement of the quench head relative to the work piece.

Apart from the construction of the quench head, per se, several important features enter into the method of the present invention. One of these features is that the quench head Q is

constrained to axial alignment with the heating head H which is also maintained in exact axial relation with the work surface being heat treated. This alignment of the quench head Q with the heating head H is accomplished by providing the upper ends of the member 11 and the mandrel 10 with recesses 39 and 40 whereby the recess 40 receives an accurately interfitting part 41 of the heating head H with the result that the quenching head is constrained to concentricity with the work surface C. Another important feature is that the work C is moved relative to the quench head Q at the same rate as it is moved relative to the heating head H. This rate of movement is uniform and may be in the nature of, for example, one inch per second depending, of course, upon the characteristics of the metal being heat treated and the rate of power input.

In practice it is preferred to have a small tolerance between the elongated barrel 34 of the quench head H and the work C being heat treated in the neighborhood of .10 of an inch or less such that during relative movement between the quench and work an injector action is provided tending to maintain the space between the quench head and the work completely filled with the quenching medium without permitting the quenching medium to back up toward the heating coil. Also, the tolerance should not be so large as to cause an ejector action tending to produce erratic quenching.

Due to the angle of projection of the quenching medium which is preferably between 25 and 45 degrees with respect to the axis of the work, as indicated at A in Figure 4, depending upon the smoothness of the work being quenched, and due to the relative movement between the work and the quench head the quenching medium engages the work surface in such manner that it is restrained from deflecting upwardly toward the head coil or the work surface being heated, to impair the heating efficiency. Here again is an important feature in the present invention. By the construction described I am enabled to arrange the initial contact of the quenching medium with the heated work surface in closely spaced axial relation with the trailing end of the heating coil so that the application of quenching medium subsequent to heating is extremely rapid, the delay being only that period of time required for the tube C to traverse the distance substantially equal to that between the trailing end of the heating coil and the orifice provided by the parallel walls 26 and 33. It is to be readily appreciated that the elapsed time between termination of heating and the application of quenching medium is relatively small since the rate of movement is preferably in the neighborhood of one inch per second. Moreover, by directing the quenching medium at an abrupt angle a more drastic quench is obtained which results in greater heat removal over a given period of time than is possible with a slight angle of quench direction.

A further step of importance is that of rotating the work during relative movement whereby the quenching medium of large volume being discharged against the heated surface under high pressure and maintained in contact therewith throughout considerable axial extent due to the close proximity of the barrel 34 of the quench head, is kept in wiping contact with the heated surface to compensate for any irregularities in quench application such as, for example, small dirt particles which may become lodged in the discharge orifice and produce erratic quenching.

There may be some tendency in the case where a rough surface is being heat treated for the quenching medium to tend to back up toward the heating coil due to the resistance to flow presented by such surface.

In order to insure against this suitable means may be provided for introducing a dry inert gas under pressure into the bore of the tubular member being heat treated ahead of the heating and quench head such that it will act directly against the discharging quenching medium and prevent flow of the same toward the heating coil. Another method of preventing backward flow of the quenching medium is to create a negative pressure within the bore between its leading end and the quench head such that an injector action is presented whereby to positively draw the annular wall of quenching medium through the annular space between the bore area undergoing quenching and the barrel of the quench head.

By thus substantially instantaneously applying a large volume of quenching medium after heating under high pressure and with little if any turbulence, and in such direction and manner as to maintain an axially flowing wall of quenching medium of considerable axial extent in contact with the heated surface at a predetermined distance from the immediate area being heated, I am enabled to control the hardness developed, the depth of hardness and the area being treated within exceedingly close limits.

In accordance with the present invention the quenching medium is applied in such volume, with such uniformity and at such an angle that the thermal energy is extracted from the annular heated zone at the same rate and rapidity as it was generated thereby preventing the same from drifting to the back metal to insure not only uniformity of hardness but also uniformity in depth of hardness.

The uniformity and rapidity in quench application attainable by the present invention is very advantageous in that it holds distortion of the work being treated to a minimum. Of greater importance, however, is the fact that by reason of the rapid quenching action herein described a fine grained martensitic structure is produced, the structure of the martensite being very much finer than that ordinarily produced by known quenching methods.

It will be noted that the mandrel 10 is recessed at 44 to threadedly receive a hollow screw 46 having radial passages 47 therein communicating with the recess 44, and that the chamber 45 below the screw 46 communicates through radial passages 49 with an annular chamber 50 defined by the mandrel 10 and a thin walled extension 51 of the member 11. These features do not form a part of the present invention. For the sake of clarity of the structure illustrated in operation these features come into play when the quench head Q is registered with the heating head H. While the two heads are being registered the screw 46 raises the ball valve 9a from its seat. This opens the passage for the flow of coolant through the heating coil so that it can be discharged. The coolant thus flows into recess 45 through the hollow screw 46 and outwardly through the passages 49 where the tubular extension 51 constrains the same to fall in an annular body straight downwardly out of contact with the walls of surrounding work C.

The quench head Q while of extremely simple construction and capable of being readily assembled and disassembled for cleaning is so con-

structed as to insure maximum efficiency of operation with the insurance that the circumferentially continuous unobstructed orifice will always be maintained in proper adjustment.

5 It is to be understood that various changes may be made in the construction and arrangement of parts without departing from the spirit of the invention as will be apparent to those skilled in the art, and that reference therefore should be had to the appended claims for a limit of the definition of the invention.

What is claimed is:

1. A quench head comprising an arbor portion having an axial quench fluid conducting passageway therein, cylindrical means coaxial with said arbor portion having axially spaced annular wall portions providing a circumferential nozzle passage and spaced annular walls extending radially inwardly from said nozzle passage wall portions 15 to provide an annular chamber radially outwardly of said axial passageway, said chamber uniformly decreasing in area in the direction of said nozzle passage, and means for radially conducting quench fluid from said axial passage uniformly 20 into said chamber throughout the inner periphery thereof, said walls being of frusto-conical formation and converging toward said nozzle passage wall portions and both inclining away from a transverse plane through said arbor portion, 25 30 said nozzle passage wall portions inclining from said chamber toward such transverse plane.

2. A quench head comprising an arbor portion having an axial quench fluid conducting passageway therein, cylindrical means coaxial 35 with said arbor portion having axially spaced annular wall portions providing a circumferential nozzle passage and spaced annular walls extending radially inwardly from said nozzle passage wall portions to provide an annular chamber radially outwardly of said axial passageway, 40 said chamber uniformly decreasing in area in the direction of said nozzle passage, and means for radially conducting quench fluid from said axial passage uniformly into said chamber 45 throughout the inner periphery thereof, said walls being of frusto-conical formation and converging toward said nozzle passage wall portions and both inclining away from a transverse plane through said arbor portion, said nozzle passage 50 wall portions having arcuate surfaces tangent to said chamber walls and parallel frusto-conical surfaces tangent to said arcuate surfaces and inclining from said arcuate surfaces toward such transverse plane.

55 3. A quenching head comprising a tubular support having a nozzle assembly supporting head, a nozzle assembly thereon comprising telescopic annular inner and outer members, the inner member having a sleeve shank and an annular outwardly extending lip at one end thereof, and the outer member being threaded on said sleeve, and having an annular lip cooperating with said first-named lip to provide an annular orifice, said sleeve shank having apertures 60 therein and said head having a passage extending radially from the inside of said tubular support, said shank apertures and said head passage being adapted to establish communication 65 between the space between said annular lips and the inside of said tubular support.

4. A quenching head comprising a tubular support having a nozzle assembly supporting head, a nozzle assembly thereon comprising telescopic annular inner and outer members, the 75 inner member having a sleeve shank and an an-

5 nular outwardly extending lip at one end thereof, and the outer member being threaded on said sleeve, and having an annular lip cooperating with said first-named lip to provide an annular orifice, said sleeve shank having apertures therein and said head having a passage extending radially from the inside of said tubular support, said shank apertures and said head passage being adapted to establish communication between the space between said annular lips and the inside of said tubular support and said head having a passage therethrough from one side thereof to a point on the other side outside of said tubular support.

6 5. The combination in a quench head of a supporting arbor having a fluid transmitting passage therein for quenching fluid, and a radially extending chamber of less flow area than said passage, nozzle forming members removably mounted on said arbor having an annular nozzle passage of progressively reduced flow area communicating with a discharge opening having a flow area no greater than the narrow portion of said passage, whereby quenching fluid flows through said arbor to said nozzle opening at a progressively increasing velocity and is expelled through said opening at its highest velocity.

7 6. The combination in a quench head of a supporting arbor having a fluid transmitting passage therein for quenching fluid, and a radially extending chamber of less flow area than said passage, nozzle forming members on said arbor having an annular nozzle passage of progressively reduced flow area communicating with a discharge opening having a flow area no greater than the narrow portion of said passage, whereby quenching fluid flows through said arbor to said nozzle opening at a progressively increasing velocity and is expelled through said opening at its highest velocity.

8 7. The combination in a quench head of a supporting arbor having a fluid transmitting passage therein for quenching fluid and a radially extending chamber of less flow area than said passage, means providing an annular nozzle opening for discharging an annular solid stream of quenching fluid from said head at a predetermined angle and having a nozzle passage connecting said chamber with said opening, the walls of said passage tapering from said chamber to said opening, whereby the flow of quenching fluid continuously increases in velocity from said arbor passage to said nozzle opening and is discharged through said opening at its highest velocity.

9 8. The combination in a quench head of a supporting arbor having a fluid transmitting passage therein for quenching fluid and a radially extending chamber of less flow area than said passage, means providing an annular nozzle opening for discharging an annular solid stream of quenching fluid from said head at a predetermined angle and having a nozzle passage connecting said chamber with said opening, the walls of said passage tapering from said chamber to said opening, and means including an ap-

10 ertured wall between said chamber and said nozzle passage for transmitting fluid evenly from said chamber to said nozzle passage, whereby the flow of quenching fluid continuously increases in velocity from said arbor passage to said nozzle opening and is discharged through said opening at its highest velocity.

11 9. The combination in a quench head of a supporting arbor having a fluid transmitting passage therein for quenching fluid and a radially extending chamber of less flow area than said passage, means providing an annular nozzle opening for discharging an annular solid stream of quenching fluid from said head at a predetermined angle and having a nozzle passage connecting said chamber with said opening, the walls of said passage tapering from said chamber to said opening, and means for transmitting fluid evenly from said chamber to said nozzle passage, whereby the flow of quenching fluid continuously increases in velocity from said arbor passage to said nozzle opening and is discharged through said opening at its highest velocity.

12 10. In the heat treatment of a longitudinal surface of a metallic article wherein successive longitudinal increments of the surface are progressively heated and quenched through the spaced application of heat and quenching fluid while effecting relative movement longitudinally of said surface between the article and the applications of heat and quenching fluid, the method of preventing the quenching fluid from flowing in a direction longitudinally toward the application of heat from the region of application of quenching fluid to said surface, which consists in directing the quenching fluid in a direction away from the region of heat application into initial contact with said surface at such pressure and angle to said surface of less than 45 degrees and so confining the quenching fluid upon contact with said surface to flow longitudinally along said surface as to produce a velocity of quenching fluid at the region of initial contact that will create a zone of negative pressure within said angle immediately adjacent said region of initial contact.

13 11. In a method of hardening a perimetral surface of a metallic article wherein successive longitudinal increments thereof are progressively heated and quenched through the spaced application of heat and quenching fluid while effecting relative movement longitudinally of said surface between the article and the applications of heat and quenching fluid, the step of directing a solid high pressure annular stream of quenching fluid in a direction away from the application of heat and quenching fluid into perimetral continuous contact with said surface at such pressure and angle to said surface of less than 45 degrees and so confining the quenching fluid to annular flow from the region of initial contact along said surface longitudinally away from the application of heat as to produce a velocity of quenching fluid at the region of initial contact that will create a zone of negative pressure within said angle immediately adjacent said region of initial contact.

HOWARD E. SOMES.
